UNITED STATES PATENT OFFICE.

PAUL SCHÜTTLER, OF CHARLOTTENBURG, GERMANY, ASSIGNOR TO PALLAS VERGASER
G. M. B. H., OF BERLIN-CHARLOTTENBURG, GERMANY

STARTING AND IDLE-RUNNING DEVICE FOR JET-CARBURETERS.

1,170,348.

Specification of Letters Patent.

Patented Feb. 1, 1916.

Application filed January 16, 1914. Serial No. 812,495.

To all whom it may concern:

Be it known that I, PAUL SCHÜTTLER, a subject of the German Emperor, and resident of Kaiser-Friedrichstrasse 7, Charlottenburg, near Berlin, Germany, have invented new and useful Improvements in Starting and Idle-Running Devices for Jet-Carbureters, of which the following is a specification.

10 This invention relates to a carbureter in which the supply of fuel during the starting of the engine, and while it is running idle, as well as while it is running under a load during the normal use, is automatically regulated, and comprises a construction of an atomizer especially adapted for the purpose so that it may perform all these functions, be safe to drive, and be easily put together.

20 The invention relates especially to the improvement that has to do with the starting and idle running. The governing, under variations of the load during normal running of the engine, forms the subject of another application, Serial No. 732,309, filed November 19, 1912, and reference may be made to the drawing of that application as showing a means for effecting that result.

If the machine is running idle, in general, 30 the throttle valve located in the carbureter will be closed, so that the machine will draw in very little air and very little fuel. In most carbureters, on account of the slight suction, the usual atomizer will either not 35 work at all, or work so unreliably that the machine cannot be set for a determined number of revolutions between the position of complete idleness and one of considerable speed. For this purpose there is generally 40 used a special opening for leading the fuel into the carbureter during the starting or idle running of the machine. The special opening belongs either to a second atomizer or is located in the wall of the carbureter 45 in the vicinity of the throttle pipe. In previous construction the fuel is conducted to these auxiliary openings through channels which are independent of the main atomizer.

In this invention the spraying pipe, in 50 addition to normal exit openings, is provided with supplemental exit openings, which, when the atomizer is located in the wall of the carbureter, are in communication with a channel in the wall of the chamber, 55 so that discharge of the fuel from these aux-

iliary openings ensues, if sufficient suction occurs in the channel.

The drawing shows in Figure 1, in cross section, a carbureter made in accordance with my invention, and in Fig. 2, a section 60 through the atomizer. Fig. 3 is an enlarged detail showing the screw *h* provided with the channel *h'*.

a is a fuel holder, *b* a nozzle, which is fastened into the atomizing tube *c*. The atomizing tube comprises the fuel exit opening *c'* for the normal engine drive, and the exit opening *c''* for the starting drive or for running idle. The openings *c'* open into the suction channel *S* of the carbureter, which channel may be closed by the throttle valve *E*. In the atomizing tube *c* is arranged an air tube *d* concentric therewith, at the upper end of which is provided a replaceable nozzle *e*, which is protected against dust by means of the filter *e'*. The openings *c''* in the atomizer *c*, discharge into a channel formed between screw threads on the upper part of the tube *c*, which channel, after the tube is placed in position, is in communication with the channel *g* in the wall of the container. The channel *g* leads to the opening *f* in the wall of the suction channel of the carbureter, at a point which lies near the edge of the closed throttle valve *E*. Between the channel *g* and the opening *f* is a replaceable screw *h* with a channel *h'*. This channel is drilled centerwise through a portion of the screw, and by means of a bend at right-angles leads to a groove *h''* in the exterior part of the screw. Said groove is in communication with channel *g*. The opening *h'* is calibrated to meet the need of the engine. It will be noted that the atomizer is continuous and integral. It will be 95 noted, moreover, that it can be withdrawn in its entirety through opening shown at the left of Fig. 1 by simply turning the nut. After withdrawal it can be examined and repaired or readjusted, and returned without disturbing any other part of the structure. No part of this tubular atomizer exceeds in diameter the diameter of the screw thread portion.

In the holder *a* is located the hinged float 105 *A*, which, in a well known manner, controls an admission valve *m*. The atomizer tube *c*, together with the air channel *d* and the regulating nozzles *b* and *e*, may be set altogether in the wall of the carbureter, or they 110

may be separated therefrom and connected wholly by means of the screw c^3 therewith. The atomizer tube extends in an oblique direction through the suction tube S , and its lower end projects into the holder a . It is provided with a packing in the wall between the suction tube and the fuel holder.

The manner in which the atomizer works is as follows: In the position of rest the level 10 of the fuel rises as high as the openings c' , or almost as high, and the fuel fills the atomizer tube c , as well as the air tube d , partly. It is a peculiarity of an atomizer that the nozzle b is directly opposite the mouth of 15 the air tube d , so that the fuel entering through the opening b has the tendency, on account of its momentum, to flow into the air tube. Since under a sudden load and consequent lowering of pressure, the fluid, 20 by virtue of its inertia, cannot quite immediately respond to variations in the air tube d and equalizer, sudden variations of the load may be avoided. Also, during variations in speed, if they should be prolonged, 25 the device adjusts itself, so that during an increased number of revolutions the fuel mixture supplied is not so rich. In this case the tube c will be entirely emptied of the fuel and will serve only to conduct air to the 30 fuel supply inside the atomizer and during the higher number of revolutions, in increasing quantity. It works also as a brake in that it dampens the abruptness of variations of the fuel supply. The nozzle e serves for 35 controlling the supply of air let in.

In conformity with the invention, in the atomizer tube c above the openings c' , are the auxiliary openings c^2 , which, while the motor is running idle, and while it is starting, come into action. The throttle E is located in the position shown in Fig. 1, and practically closes the suction channel S . At the opening f in the wall of the suction channel there is a restricted passage. Engine 40 suction through here causes suction in the channel g , so that fuel is drawn into the space between the atomizer tube c and the air tube d and is discharged through the 45 openings c^2 . The suction at the openings c' , because of the small velocity of the air at this part of the channel, is so small that the exhaust at the opening c^2 overcomes it. Air, 50 therefore, enters the opening c' and forms a mixture with the fuel and the mixture discharged from the openings c^2 . The position 55 of the throttle valve and the fine adjustment of the opening in the screw h , make it possible so to regulate the mixture that the device may be adapted to the "running idle" 60 of the machine. If the throttle valve is more or less opened the suction in the channel g will be correspondingly weakened or strengthened, and in turn the suction at the main openings c' in the suction channel S , 65 correspondingly increased or diminished.

The pull through the openings c^2 will cease when the throttle valve is in that position in which the pull through the main injection openings c' surpasses that through the openings c^2 . The superseding of the auxiliary injection by the normal injection occurs entirely automatically. A further distinction of the discovery is the specially convenient construction and location of the injector which, as a whole, can be easily unscrewed and removed without disturbing the structure of the carbureter.

Having thus described my invention what I claim as new and desire to secure by Letters Patent is:

1. In combination, in a carbureter, a continuous atomizer extending across the air channel and provided with main discharge openings arranged to discharge into the air channel and also with auxiliary discharge 85 openings, and, in the wall of the fuel container, a conduit, discharging into the air channel, the auxiliary discharge openings of the atomizer being in communication with such channel.

2. In combination, in a carbureter, a throttle valve therefor, a continuous atomizer extending across the air-channel and provided with main openings arranged to discharge into the air channel of the carbureter, and 95 provided also with auxiliary discharge openings, and, in the wall of the fuel container, a channel arranged in communication with the auxiliary discharge openings discharging into the air channel of the carbureter at or near the edge of the throttle valve in its closed position, there being provided a small passageway between the edge of the throttle valve and the wall of the air channel.

3. In a carbureter, and in combination therewith a continuous atomizer extending across the air-channel and provided with main jet orifices discharging into the air intake channel, and also provided with auxiliary openings discharging into an auxiliary channel, said auxiliary channel discharging into the intake channel, and an open-ended air pipe center-wise of the atomizer, arranged to supply air to said atomizer and thereby control and regulate fuel supply in response to variations of engine load.

4. In a carbureter, a throttle valve therefor, an atomizer arranged obliquely across the air intake channel, and having openings discharging directly into said channel, the lower end of said atomizer having direct connection with the fuel supply chamber, and an open-ended pipe arranged center-wise of said atomizer, and communicating freely with said atomizer, said atomizer being provided with an auxiliary discharge opening, communicating with the air intake channel, on the engine side of the throttle 130

valve, whereby when the throttle is closed suction may come through said auxiliary openings and air be drawn downward through the air pipe and upward through 5 the channel-discharge openings.

5. In a carbureter, an atomizer provided at its upper part with two screw threads and a channel between said screw threads, and also provided with discharge openings, 10 said atomizer arranged to extend obliquely across the air intake channel and supported by said screw threads in the wall of the carbureter so that its lower end communicates with the fuel chamber, the walls of 15 said carbureter being provided with a channel leading from the atomizer channel to the air intake channel through said openings.

6. In a carbureter, and in combination 20 therewith, a continuous channeled atomizer provided with discharge openings and arranged to extend obliquely across the air intake channel and supported in the wall of the carbureter so that its lower end communicates with the fuel chamber, and the wall 25 of the carbureter being provided with a channel communicating with said channel

in the atomizer and with the intake channel near the throttle valve.

7. In a carbureter, in combination, a continuous tubular atomizer, a screw thread on the upper end of said atomizer, the wall of the carbureter provided with a hole with which said screw may engage, a seat on the other side of the carbureter, the seat and 35 opening being so arranged that the atomizer will be held obliquely in the air channel, and discharge openings about the middle of said atomizer, said atomizer provided with a channel connected at its lower end with 40 the fuel supply and also connected with the discharge openings, the said atomizer being removable and replaceable as an entirety without disturbing other features of the 45 structure.

In testimony, that I claim the foregoing as my invention, I have signed my name in presence of two witnesses, this 5th day of January, 1914.

PAUL SCHÜTTLER.
